United States Patent Office

Des. 228,417
Patented Sept. 18, 1973

228,417

MULTI-PURPOSE DESK ACCESSORY

Walter Riley, 7955 Riggs Road (No. 9),
Adelphi, Md. 20783

Filed July 23, 1971, Ser. No. 165,864

Term of patent 14 years

Int. Cl. D19—02

U.S. Cl. D74—5 A

FIG. 1.

FIG. 2.

FIG. 3.

FIG. 4.

FIG. 1 is a front perspective view of a multi-purpose desk accessory showing my new design;

FIG. 2 is a rear perspective view thereof;

FIG. 3 is another front perspective view thereof as it appears with the panel in raised position to reveal the mirror; and

FIG. 4 is a top plan view thereof with the panel in lowered position.

I claim:

The ornamental design for a multi-purpose desk accessory, as shown.
